United States Patent Office

Des. 178,854
Patented Sept. 25, 1956

178,854

BASE FOR ELECTRIC MIXER

Chauncey E. Waltman, Chicago, Ill., assignor to Nu Tone,
Inc., Cincinnati, Ohio, a corporation of New York

Application September 2, 1955, Serial No. 37,753

Term of patent 14 years

(Cl. D44—1)

Fig. 2

I claim:

The ornamental design for a base for electric mixer, substantially as shown.
